UNITED STATES PATENT OFFICE.

CHARLES E. BULTMAN, OF CHICAGO, ILLINOIS; IDA MAI BULTMAN EXECUTRIX OF SAID CHARLES E. BULTMAN, DECEASED.

DESIGN FOR A PITCHER OR THE LIKE.

Application filed November 10, 1922. Serial No. 4,252. Term of patent 3½ years.

To all whom it may concern:

Be it known that I, CHARLES E. BULTMAN, a citizen of the United States, residing at Chicago, in the county of Cook and State of Illinois, have invented a new, original, and ornamental Design for Pitchers or the like, of which the following is a specification, reference being had to the accompanying drawing, forming part thereof.

The figure is a front view of a pitcher or the like, showing my new design.

I claim:

The ornamental design for a pitcher or the like as shown.

In witness whereof I affix my signature.

CHARLES E. BULTMAN.
